UNITED STATES PATENT OFFICE.

EVERETT IRVING ROGERS, JR., OF PROVIDENCE, RHODE ISLAND.

DESIGN FOR A DISPLAY TRAY.

Application filed November 7, 1924. Serial No. 11,311. Term of patent 7 years.

To all whom it may concern:

Be it known that EVERETT IRVING ROGERS, Jr., a citizen in the United States, residing at 360 Lloyd Ave., Providence, in the county of Providence and State of Rhode Island, has invented a certain new, original, and ornamental Design for Display Trays, of which the following is a specification, reference being had to the accompanying drawing, forming a part thereof.

The figure is a perspective view of a display tray showing my new design.

I claim:

The ornamental design for a display tray substantially as shown.

In testimony whereof I affix my signature.

EVERETT IRVING ROGERS, JR.
